UNITED STATES PATENT OFFICE.

CHARLES F. BOSTOCK, OF LITTLE SILVER, NEW JERSEY, ASSIGNOR TO LA PIERRE MANUFACTURING COMPANY, OF NEWARK, NEW JERSEY, A CORPORATION.

DESIGN FOR A BACK OF A MIRROR OR SIMILAR ARTICLE.

Application filed July 9, 1925. Serial No. 14,039. Term of patent 7 years.

To all whom it may concern:

Be it known that I, CHARLES F. BOSTOCK, a citizen of the United States, residing in the town of Little Silver, county of Monmouth, and State of New Jersey, have invented a new, original, and ornamental Design for a Back of a Mirror or Similar Article, of which the following is a specification, reference being had to the accompanying drawing, forming part thereof.

Figures 1 and 2 of the drawing are respectively plan and side views of a back for a mirror, or similar article showing my new design.

I claim:

The ornamental design for a back of a mirror or similar article as shown.

CHARLES F. BOSTOCK.
